UNITED STATES PATENT OFFICE.

WILLIAM A. POIDA, OF CHICAGO, ILLINOIS.

BEADWORK LOOM.

Application filed June 7, 1923. Serial No. 643,893.

To all whom it may concern:

Be it known that WILLIAM A. POIDA, a former subject of the King of England, and a resident of the city of Chicago, county 5 of Cook, and State of Illinois, who has forsworn his allegiance to said King of England and declared his intention of becoming a citizen of the United States, and therefore is not now a citizen or subject of any 10 country, has invented certain new and useful Improvements in Beadwork Looms, of which the following is a specification.

My invention relates to new and useful improvements in bead-work looms and has 15 for its object to provide a handy and efficient loom for making bead watch fobs, necklaces, bracelets, belts, etc., and in which all the work supporting and holding elements may be readily adjusted, reset, or 20 replaced to suit the size and material of the particular article to be woven on said loom.

Other objects will appear hereinafter.

The invention consists in the combinations 25 and arrangements of parts hereinafter described and claimed.

The invention will be best understood by reference to the accompanying drawing forming a part of this specification and in 30 which,

Fig. 1 is a plan view of my improved loom with warp threads mounted in position thereon,

Fig. 2 is a side view thereof, showing in 35 dotted outline the supporting mechanism at one end of the loom reset for weaving a shorter article, and

Fig. 3 is an enlarged cross sectional view.

My improved device comprises a base 40 member or frame bar 6 of wood or any other suitable material which may be penetrated or has a penetrable upper portion and which is sufficiently rigid to retain its shape; and further comprises a supporting member 45 7, which may consist of a strong wire rod bent in the shape of a yoke or inverted U with sharpened ends, or any other suitable rigid member provided with sharpened lower portions, whereby the work supporting members may be readily mounted or reset at any desired position on the base member 6 by pressing said sharpened ends or portions into the base member, substantially as indicated in the drawing. A coiled spring 50 8 or similar suitable means is removably mounted on the upper or yoke part of sup-

porting member 7 and provides spaces for receiving the warp threads 9 which the coils of said spring hold laterally in spaced relation. The spaces between the coils of the spring substantially agree with the width of the beads used for making an article, and when it is desired to make an article with smaller or with larger beads, a spring with its coils closer together or more extended 55 may readily be substituted for the one on the supporting member 7. This construction affords a valuable improvement over the present supporting members which invariably have the notches cut on the upper portion to hold the warp threads in position.

The means provided for holding the warp threads taut or longitudinally in position comprises a single member 10 placed outward of each work supporting member 7 and its provided with a sharp end, preferably a threaded end, for conveniently driving said member into the penetrable base member 6, and with a hooked or bent over 60 upper portion 11 for receiving and holding the parts of the warp threads forming the ends of the article.

It will be apparent from the above disclosure that the supporting and holding members 7 and 10 may be readily withdrawn from the base board and reset thereon at any desired or required position to suit the particular length of the article to be woven on said member; and furthermore that the 65 coiled spring 8 may be readily exchanged in order to provide the exact spacing means for spacing the warp threads to suit the width of the beads used for the article woven on said loom.

While I have illustrated and described the preferred form of construction for carrying my invention into effect, this is capable of variation and modification without departing from the spirit of the invention. I, therefore, do not wish to be limited to the precise details of construction set forth but desire to avail myself of such variations and modifications as come within the 70 scope of the appended claims.

Having described my invention what I claim as new and desire to secure by Letters Patent is:

1. A bead work loom comprising a base member, supporting members resetably mounted on said base member, extensible resilient means removably mounted on each 75 110

supporting member for receiving and spacing the warp threads of articles to be made on said loom, and means for holding the warp threads taut during construction.

5 2. A bead work loom comprising a base member, yoke members resettably mounted on said base member, coiled means removably mounted on each yoke member for spacing the warp threads, and members 10 mountable in various positions longitudinally on said base member for holding the warp threads in operative position.

15 3. A bead work loom comprising an integral base member, supporting members resettably mounted on said base member, means on said supporting members for spacing the warp threads, and a single threaded member resettably mounted on said base member outward of each supporting member 20 for holding said warp threads in proper position.

25 4. A loom for making bead work articles, said loom comprising a base with a penetrable portion, members for supporting said article during construction and provided with sharpened parts pressable into said penetrable portion of the base member, removable means on said supporting members providing spaces for retaining the warp 30 threads in proper lateral position, and means for holding said warp threads longitudinally in position.

35 5. A loom for weaving bead work articles and comprising a base member of wood, supporting means with parts pressable into said wooden base for mounting said supporting means in its proper position, means on said supporting means for retaining

threads of said article in proper lateral position, and means drivable into said base 40 in any desired position for holding said threads taut.

6. A bead work loom comprising a base, yokes with sharpened ends pressable into said base at any required position, coiled springs mounted on said yokes for properly spacing the warp threads, and means readily resettable on said base to suit the length of the article and for holding the warp threads taut. 50

7. A loom for weaving bead work articles which comprises a base member of wood, supporting yokes with sharpened ends pressable into said wooden base, coiled springs mounted on said yokes for retaining warp threads spaced, and threaded pins fastenable into said base at any suitable position for holding said threads taut. 55

8. A loom comprising penetrable base means, work supporting means having means for penetrating said base means to mount said supporting means at various positions thereon, means removably mounted on said supporting means and providing equal spaces thereon, and means with ends 60 to penetrate and be held in said base means for holding threads in said spaces on said supporting means. 65

In testimony whereof I have signed my name to this specification in the presence 70 of two subscribing witnesses.

WILLIAM A. POIDA.
